[57] CLAIM

The ornamental design for an impeller paddle, as shown and described.

DESCRIPTION

FIG. 1 is a perspective view of an impeller paddle, showing my new design;

FIG. 2 is a top plan view thereof;

FIG. 3 is a bottom plan view thereof;

FIG. 4 is a left side elevational view thereof;

FIG. 5 is a rear elevational view thereof;

FIG. 6 is a front elevational view thereof;

FIG. 7 is a perspective view of a second embodiment of FIG. 1, the only difference being the top liner has been removed;

FIG. 8 is a top plan view of FIG. 7;

FIG. 9 is a bottom plan view of FIG. 7;

FIG. 10 is a left side elevational view of FIG. 7;

FIG. 11 is a rear elevational view of FIG. 7;

FIG. 12 is a front elevational view of FIG. 7;

FIG. 13 is a perspective view of a third embodiment of the impeller paddle showing my new design;

FIG. 14 is a top plan view of FIG. 13;

FIG. 15 is a bottom plan view of FIG. 13;

FIG. 16 is a left side elevational view of FIG. 13;

FIG. 17 is a rear elevational view of FIG. 13; and,

FIG. 18 is a front elevational view of FIG. 13.
